DESIGN FOR A COMPACT

Sadye Elaine Wallace, New York, N. Y.

Application June 14, 1937, Serial No. 69,842

Term of patent 3½ years

To all whom it may concern:

Be it known that I, Sadye Elaine Wallace, a citizen of the United States, residing at New York, in the county of New York and State of New York, have invented a new, original, and ornamental Design for a Compact, of which the following is a specification, reference being made to the accompanying drawing, forming part thereof.

The figure is a perspective view of a compact showing my new design, in which the cover and edge only are shown, the back being plain, and the cover is provided with an opening through which illustrations on an inner surface may be seen.

I claim:

The ornamental design for a compact as shown and described.

SADYE ELAINE WALLACE.
